Specification for Design.

Patented May 31, 1921.

Application filed July 22, 1920. Serial No. 398,323. Term of patent 14 years.

To all whom it may concern:

Be it known that I, CHARLES F. SMITH, a citizen of the United States, and residing in the city of Chicago, county of Cook, and State of Illinois, have invented a new, original, and ornamental Design for Vegetable-Peeling Disks, of which the following is a specification, reference being had to the accompanying drawings, forming a part thereof.

In the drawings:

Figure 1 is a top plan view of the disk.
Fig. 2 is a side elevation thereof.

Fig. 3 is another side elevation showing a different circumferential part.

I claim:

The ornamental design for a vegetable peeling disk as shown.

CHARLES F. SMITH.
